UNITED STATES PATENT OFFICE.

NEWELL G. AUGIR, OF BROOKLYN, NEW YORK.

STREET-SIGNAL FOR CARS.

No. 899,499.

Specification of Letters Patent.

Patented Sept. 29, 1908.

Application filed June 28, 1907. Serial No. 381,188.

To all whom it may concern:

Be it known that I, NEWELL G. AUGIR, a citizen of the United States, and residing at Brooklyn, in the county of Kings and State 5 of New York, have invented certain new and useful Improvements in Street-Signals for Cars, of which the following is a specification, such as will enable those skilled in the art to which it appertains to make and use the 10 same.

This invention relates to tramways and tramway cars; and the object thereof is to provide an ordinary tramway car with an improved apparatus for visually signaling 15 or indicating to passengers within the names or numbers of cross streets or avenues which cross the line of the tramway, or the street in which the tramway is located, as the car approaches such cross streets or 20 avenues.

In the accompanying drawing, I have shown my improvement applied to what is known as an overhead trolley system and the invention is fully disclosed in the following specification, of which the accompanying 25 drawing forms a part, in which the separate parts of my improvement are designated by suitable reference characters in each of the views, and in which,—

Figure 1 is a sectional side view of one end of a car provided with my improved signal device or apparatus and showing a part of a trolley wire and a hanger suspended from one of the supports of the wire and adapted 30 to operate my improved signal device or apparatus; Fig. 2 a sectional side view of the signal device or apparatus detached from the car but showing the same in the same position as in Fig. 1; Fig. 3 a sectional plan view 35 of the signal device or apparatus as shown in Fig. 2; Fig. 4 a view similar to Fig. 2 but showing the signal device or apparatus reversed; Fig. 5 a sectional end view of a 40 spring roller which I employ; Fig. 6 a sectional side view of said roller and showing other parts connected therewith.

In the drawing forming part of this specification, I have shown my improvement applied to what is known as an overhead trolley 45 tramway system and at *a* I have shown one end portion of a car provided with the usual projecting hood *a*², platform *a*³ and dash board *a*⁴, and in the practice of my invention, I secure in the end of the car, over the 50 hood *a*², a box or case *b* which contains the principal part or parts of my improved signal

device or apparatus. The box or case *b* is provided in its inner end, as shown in Fig. 2, with an opening *b*² preferably closed by a transparent panel *b*³ and the outer end of 60 the box or case *b* is preferably provided with an upwardly directed extension *b*⁴ which is open at the top and shown in said figure.

Mounted in the opposite end portions of the case *b* are two spring drums or rollers *c* 65 and *d*, and these spring drums or rollers are made in a manner somewhat similar to what is known as the Hartshorn window shade roller, and the spring drum or roller *d* is shown in Figs. 5 and 6, but said spring drums 70 or rollers *c* and *d*, except for the difference hereinafter pointed out are of the same construction, and a detail or sectional view of the spring drum or roller *c* is not given. Each of the rollers *c* and *d* comprises, in the construction thereof, a central body portion *d*² and an outer drum-shaped portion *d*³, and the central body portion *d*² is provided with end shafts *d*⁴ which may consist, if desired, of a single shaft passed longitudinally 75 through the central body portion *d*², and the end shafts *d*⁴ are passed through the ends of the outer drum-shaped portion *d*³, and wound on the central body portion *d*² is a spiral spring 80 *d*⁵ one end of which is secured to the central 85 body portion *d*² and the other to the outer drum-shaped portion *d*³. The spring drum or roller *c* is provided with end disks *e* and *f*, and the end disk *f* is provided with a central sleeve *f*², and said sleeve is provided with a 90 rigid pulley *f*³. The spring drum or roller *d* is provided at one end with a disk *g*, and adjacent to the opposite end is another disk *h*, and the disk *g* corresponds with the end disk 95 *e* of the spring drum or roller *c*, and the disk *h* of the spring drum or roller *d* is independent of said drum or roller and rotatable on the shaft *d*⁴ thereof and provided with a rigid sleeve *h*² having a rigid pulley *h*³, and the pulleys *f*³ and *h*³ are geared in connection 100 by a belt *h*⁴ or in any desired manner. The end disk *h* of the spring drum or roller *d* is also provided with a plurality of pins *h*⁵ arranged in a circle on the outer side thereof and near the perimeter thereof, and the end 105 disk *g* of the spring drum or roller *d* is provided on the outer side thereof with pins *g*² arranged in a circle thereon near the perimeter thereof, and said disk *g* is also provided with a plurality of teeth *g*³, six of which are 110 shown, and the teeth *g*³ as shown are spaced equally with the pins *g*². The end disk *e* of

the spring drum or roller c is provided with pins e^2 on the outer side thereof and arranged in a circle thereon near the perimeter thereof, and said disk is also provided with 5 a plurality of teeth e^3 similar in form and number to the teeth g^3 , and the pins e^2 are arranged similar to the pins g^2 , and the pins e^2 and g^2 in the construction shown equal in 10 number the teeth e^3 and g^3 . The springs d^2 in the spring drums or rollers c and d are wound in opposite directions, or so that they exert their force in opposite directions as indicated by the arrows x and x^2 in Fig. 2, and wound on said spring drums or rollers is a 15 flexible strip or sheet i of any preferred material on which are printed, painted, or otherwise placed, the numbers of the cross streets along the line of the tramway as indicated in Fig. 3. The box or case b is provided 20 with a transverse support i^2 having upright members i^3 provided with slots i^4 , and mounted transversely on the strip or sheet i between the drums or rollers c and d is a roller i^5 which rests on said strip or sheet 25 and is provided with end trunnions i^6 movable in the slots i^4 of the uprights i^3 , and the roller i^5 is designed to hold the strip or sheet i taut.

Pivoted to the support i^2 adjacent to the 30 opposite sides thereof are pawls j and j^2 connected by a horizontal link j^3 , and the pawl j^2 is adapted to operate in connection with the teeth g^3 of the spring drum or roller d , and the pawl j is adapted to operate in connection 35 with the teeth e^3 of the spring drum or roller c , and connected centrally with the link j^3 is a cord k the opposite end portions k^2 and k^3 of which are passed over pulleys or rollers k^4 at the opposite sides of the supports 40 and passed downwardly through the bottom of the box or case b and provided with handles k^5 and k^6 , and by means of the opposite end portions k^2 and k^3 of the cord k , the pawls j and j^2 may be swung into different 45 positions so that the pawl j will operate in connection with the teeth e^3 of the drum or roller c , or the pawl j^2 will operate in connection with the teeth g^3 of the drum or roller d , and in Fig. 3 of the drawing the said pawls 50 are shown in this last named position.

Pivoted in the side portion of the top part b^4 of the box or case b over the end disk g of the spring drum or roller d is a lever m provided at its lower end with a pawl or pivoted 55 member m^2 adapted to operate in connection with the pins g^2 of the disk g , and the pawl or pivoted member m^2 may swing freely in one direction, but the end of the lever m is provided with a stop m^3 which prevents it from 60 swinging in the opposite direction.

Pivoted in the side top portion b^4 of the box or case b and near the outer end of said box or case b and over the end disk h of the drum or roller d is a lever n similar to the 65 lever m , and provided at its lower end with a

pawl or pivoted member n^2 similar to the pivoted member m^2 of the lever m and adapted to operate in connection with the pins h^2 on the disk h and said pawl is free to swing in one direction but the movement of 70 which in the other direction is limited by a stop n^3 on the lower end of said lever.

An arm o is pivoted to the case b adjacent to the lower inner side of the spring drum or roller c and just outside of the end disk e 75 thereof, and said arm is provided with a bottom extension o^2 having a pivoted stop o^3 , the lower end of which is weighted as shown at o^4 , whereby said pivotal stop is always held in the vertical position and the arm o 80 always bears on one of the pins e^2 on the end disk e of the spring drum or roller c , and the pins e^2 on said disk are also adapted to operate on the upper end of the stop o^3 .

In Fig. 1 of the drawing, I have shown at p 85 a trolley wire, and, in practice, I connect with the supports p^2 thereof, but one of which is shown, hangers p^3 having flexible supports p^4 and adapted to operate the levers m and n , and it will be understood that, in 90 practice, the hangers p^3 are placed adjacent to or between each of the cross streets indicated by name or number on the strip or sheet i , and the operation will be as follows. The levers m and n are provided at their upper ends with heads m^4 and n^4 , and if the car a be moving in the direction of the arrow y Fig. 1, as the car approaches the cross street, one of the hangers p^3 will strike the head m^4 of the lever m and force said lever into the 95 position shown in Fig. 2. This operation will turn the spring drum or roller d one step, and the spring drum or roller c will be turned one step by the strip or sheet i and the name of the cross street that the car is approaching 100 will be shown on the spring drum or roller c through the opening b^2 in the inner end of the box or case b in such position as to enable it to be read by anyone in the car, and this operation will be repeated at each street 105 crossing, or just after leaving said crossing, or the hangers p^3 may be located at any desired point between the cross streets so as to indicate the next cross street when the car passes under said hanger. The pawls j and 110 j^2 are intended to prevent any sudden backward movement of the spring drums or rollers c and d , and when the car is going in the direction indicated by the arrow y in Fig. 1, the pawl j^2 will be in operation in connection 115 with the spring drum or roller d as shown in Fig. 2, but when the car is moving in the opposite direction the pawl j will be in operation in connection with the spring drum or roller c . 120

It will also be understood that when the car reaches the end of the line and starts back on another track without being turned around and is moving in the direction of the arrow y^2 in Fig. 1, the lever n is operated, 125 130

suitable hangers p^3 being provided for this purpose, and in this movement of the car each time that said car passes under one of the hangers p^3 , the lever n and pawl or pivot-
5 ed member n^2 thereof will be operated so as to turn the disk or wheel h , and by means of the pulleys h^3 and f^3 and the belt h^4 the spring drum or roller c will be turned one step in the direction of the arrow x and the
10 spring drum or roller d will also be turned one step in the same direction by the strip or sheet i , and the name of the cross street which the car is approaching will be shown through the opening b^3 in the inner end of the
15 box or case b so that it may be read by any person or persons in the car. The arm o is also intended to regulate the movement of the spring drums or rollers c and d and particularly the movement of the spring drum
20 or roller c , especially in case of any sudden jerk, or jolt, or jar of the car, or a quick movement thereof when passing under the hanger or hangers p^3 ; but this arm is not absolutely necessary and may or may not be
25 employed.

The object of the spring or springs d^4 in the spring drums or rollers c and d is to keep the strip or sheet i wound taut at all times on said spring drums or rollers, and it will also
30 be apparent that these springs may be dispensed with under certain conditions, or in other words they are not an absolutely essential feature of my invention, and the same object may be accomplished by other means.

35 It will be understood that the pivoted pawls or members m^2 and n^2 on the levers m and n swing freely over the pins g^2 and h^5 on the disks g and h when the levers m and n move in one direction, but engage said pins
40 when said levers are moved in the opposite direction in order to turn the spring drum or roller d or the disk h as hereinbefore described.

Although I have shown and described my
45 device applied to what is known as an overhead trolley tramway system, it will be apparent that my invention is not limited to a tramway system of this class.

It will thus be seen that by means of my
50 improvement I provide a simple and effective device or apparatus for the purpose specified, and one which may be conveniently applied and operated.

55 My invention is not limited to the particular details and construction shown and described, and various changes therein, and modifications thereof may be made, within the scope of the appended claims, without departing from the spirit of the invention or
60 sacrificing its advantages.

Although, I have described my signal device or apparatus as particularly designed for use in tramway cars in cities, and for visually signaling the numbers or names of
65 the cross-streets, it will be apparent that the

same may be employed on other car lines for visually signaling the names of stations.

Having fully described my invention, what I claim as new and desire to secure by Letters Patent, is:—

70 1. In an apparatus of the class described, a casing, two rollers mounted therein, said rollers being composed of central stationary parts, and drums mounted thereon, and between which are placed oppositely operating tension devices, said drums being adapted to rotate on the central stationary parts, ratchets and pins carried by said drums, a disk loosely mounted on an end extension of one of said stationary parts, said disk being 75 geared in connection with the opposite drum, pawls operating in connection with said ratchets, said disk being also provided with spaced pins, and devices operating in connection with the pins on one of said drums and 80 with the pins on said disk to rotate both of said rollers.

2. In an apparatus of the class described, a casing, rollers mounted therein, opposed ratchets and spaced pins carried by said rollers, a disk loosely mounted adjacent to one of said rollers and geared in connection with the other of said rollers, spaced pins carried by said disk, a flexible sheet mounted on said rollers, means co-acting with the pins of one 90 drum to operate the sheet in one direction, means co-acting with the pins of the disk to operate the sheet in the opposite direction and a retarding device operating in connection with the pins of one of said rollers. 95

3. In a street signal apparatus for cars, a casing, parallel stationary shafts mounted in said casing, rollers mounted on said shafts, a flexible sheet wound on said rollers, a disk mounted on one of said shafts, pins carried 100 by one of said rollers and by said disk, means operating in connection with the pins of said roller to give said roller a step by step rotation when the car is going in one direction and means operating in connection with the 105 pins of the disk to give said disk a step by step rotation when the car is going in the opposite direction, said disk being geared in connection with the opposite roller.

4. In a street signal apparatus for cars, a 110 casing, parallel stationary shafts mounted in said casing, rollers mounted on said shafts, a flexible sheet wound on said rollers, a disk mounted on one of said shafts, pins carried by one of said rollers and by said disk, means 115 operating in connection with the pins of said roller to give said roller a step by step rotation when the car is going in one direction and means operating in connection with the pins of the disk to give said disk a step by 120 step rotation when the car is going in the opposite direction, said disk being geared in connection with the opposite roller, spaced pins on said opposite roller and a retarding device mounted adjacent to the last named 125 130

4
roller and adapted to operate in connection with said pins.

5. In an apparatus of the class described, a casing, rollers mounted therein, opposed ratchets and spaced pins carried by said rollers, a disk loosely mounted adjacent to one of said rollers and geared in connection with the other of said rollers, spaced pins carried by said disk, a flexible sheet mounted on said 10 rollers, means co-acting with the pins of one drum to move the sheet in one direction, and

means co-acting with the pins of the disk to move the sheet in the opposite direction.

In testimony that I claim the foregoing as my invention I have signed my name in presence of the subscribing witnesses this 26th day of June 1907. 15

NEWELL G. AUGIR.
